ABSTRACT

The packing box includes a plurality of side wall parts, a bottom wall part, a housing part, an outer lid part, a tuck, an extending part, an inner flap, a slit, and an obstructive part. The obstructive part is folded along the side edge that crosses the other side wall part of the inner flap. Once the tuck is inserted, the extending part restricts the release of the outer lid part by being restored to the original state in the direction that crosses the extending direction of the slit. The obstructive part is placed in the course that reaches from the clearance between the top edge of the side wall part, the top edge crossing the other side wall part, and the inner flap to the extending part, whereby obstructing the approach from the outside of the packing box to the extending part.

PACKING BOX

INCORPORATION BY REFERENCE

The disclosure of Japanese application No. 2015-014505 filed on Jan. 28, 2015 including the specification, drawings, and abstract is incorporated herein by reference in its entirety.

BACKGROUND

This disclosure relates to a packing box.

At the time of conveyance of the precision devices and apparatuses such as an image forming device represented by a digital multifunction peripheral, or an information appliance, the devices and apparatuses are packed for the purpose of preventing breakage of or damage to the device and apparatuses during conveyance. To pack the device, packing boxes made of corrugated fiberboard or the like material may be used.

Some techniques about the packing of devices and apparatuses have been already disclosed.

As an example, a knockdown packing box that is made of corrugated fiberboard and is in a hexahedron shape having four side faces that is consecutively provided to surround the bottom face is disclosed. In a fabricated state, this packing box has appropriate boundaries and an opening to observe articles (contents) in the box on the bottom surface.

As another example, a cushion material for packing is disclosed. This cushion material for packing is formed of a cushion material and is used to maintain the clearance between either the undersurface or the four side surfaces of packed articles and the inner surface of the packing box. This cushion material comprises a corrugated fiberboard sheet, and the both sides of the material are provided with rectangular sleeves the section of which is in an approximately rectangular shape. Furthermore, a U-shaped sleeve having an approximately U-shaped section is disposed such that it is perpendicular to the rectangular sleeves. This U-shaped sleeve can lock the upper parts of the both ends of the rectangular sleeves at the upper parts of the both ends of the U-shaped sleeve.

As still another example, the packing box which is consecutively provided with a bottom plate, side plates and a top plate, to form a wide tube, is disclosed. A plurality of mountain fold lines are formed from one end to another end of the bottom plate such that the plurality of mountain fold lines are arranged in parallel. Similarly, a plurality of valley fold lines are formed from one end to another end of the top plate such that the plurality of mountain fold lines are arranged in parallel. This bottom plate is to be folded along the mountain fold lines such that the lower surface of the bottom plate should be protruded. Then, the top plate is to be folded along the valley fold lines such that the upper surface of the top plate should be recessed. In a stacked state, the top surface of the lower box is fitted into the bottom surface of the upper box. End plates are extended from each of the bottom plate, the side plates and the top plate and these end plates are engaged with each other, to close the edge face of the wide tube. The shape of the wide tube is thus maintained. Then, the projecting part is provided on the end plate that extends from the side plate. This end plate that extends from the side plate and the end plate that extends from the top plate are meshed with each other via the projecting part, and then the end plate that extends from the bottom plate is engaged therewith. Then, the outer vertical plate provided consecutively on one end of the bottom plate

2

is raised, and the lower part of the side vertical plate provided consecutively on either side of outer vertical plate is superposed on the outer surface of the side plate. The inner vertical plate provided consecutively with the side vertical plates is arranged in an opposite position to the outer vertical plate, to form a vertical tube. Furthermore, the pillar piece of the side plates is wrapped with the vertical tube, and lock pieces that are provided on the lower part of the side vertical plates are inserted into lock holes that are provided at the lower part of the side plates.

As yet another example, a corrugated fiberboard packing box with an automatically-lockable bottom is disclosed. This packing box includes a multi-layer corrugated fiberboard sleeve that is freely changeable between a square cylindrical fabricated form and a flat folded form. The bottom of the box is closed by an automatically-lockable bottom wall. The sleeve has four side wall parts provided consecutively in parallel via vertical lines. The side wall parts consists of multi-layered corrugated fiberboards which have three or more layers. In the fabricated form, the box is formed so as to be folded into a flat form along a pair of vertical ruled lines which are located diagonally. Each of the side wall parts of the sleeve has a lower ledge, and the automatically-lockable bottom wall is formed by bottom wall constitution plates which are attached to the lower ledge of the side wall parts. When the sleeve is folded into a flat form, each of the bottom wall constitution plates is also folded, and when the sleeve is fabricated in a square cylindrical shape, each of the bottom wall constitution plates spreads to close the bottom of the sleeve.

As yet another example, the packing box for automobile bumpers is disclosed. This packing box consists of an inner box part which is intended to wrap the middle portion of a bumper and a pair of side box portions which is intended to wrap the both sides of the bumper, a base, opposed edge plates, and a lid plate. In this packing box, edge plates are bent according to the angle between an intermediate portion and the both side parts of the bumper over the portion from the inner box part to a pair of side box parts. In the inner box part, edge plates are coupled to the base directly. In the side box part, the base is formed in a tapered shape according to the shapes of the both side parts of the bumper. A folding piece is placed between the base and the edge plates, and the base and the edge plates are folded along the ruled line of the boundary between the inner box part and the side box part. Then, the inserting piece is interfolded along the central valley fold line.

SUMMARY

According to one aspect of this disclosure, the packing box includes a plurality of side walls, a bottom wall part, a housing part, an outer lid part, a tuck, an extending part, an inner flap, a slit, and an obstructive part. The plurality of side walls compose peripheral walls. The housing part is composed of the plurality of side walls and the bottom wall part, and houses an article to be packed. The outer lid part is provided consecutively with one side wall part of the plurality of side wall parts and opens and closes the upper part of the housing part towards the opposed other side wall part. The tuck extends from the tip edge of the outer lid part, and is to be folded along the tip edge. The extending part crosses the tip edge of the tuck and extends from the side edge. The inner flaps are provided consecutively with other side wall part and are to be folded inward. The inner flap is provided with the slit, which is cut along the other side wall part. The obstructive part is configured to be folded along a

folding part crossing the other side wall part. The tuck is configured to be inserted into the slit while the extending part is folded. Once the tuck is inserted, the extending part restricts the release of the outer lid part by being restored to the original state in the direction crossing the extending direction of the slit. The obstructive part is configured to be placed in the course that reaches from the clearance between the top edge of the side wall part which crosses the other side wall part, and the inner flap to the extending part, whereby obstructing the approach from the outside of the packing box to the extending part.

BRIEF DESCRIPTION OF THE DRAWINGS

FIG. 1 shows a schematic perspective view of the packing box according to one embodiment of this disclosure.

FIG. 2 shows a development view illustrating a corrugated fiberboard member before fabrication of the packing box according to one embodiment of this disclosure.

FIG. 3 shows a development view illustrating a state where the corrugated fiberboard member as illustrated in FIG. 2 does not have the projecting part, which is described below.

FIG. 4 shows a flow chart illustrating a representative process of fabricating the packing box in which the toner cartridge is housed.

FIG. 5 shows a view illustrating a folded state of an extending part which is folded inwards.

FIG. 6 shows a view indicating a state where the tuck and a pair of extending parts are being inserted into the slit while the state where a pair of extending parts are folded is maintained.

FIG. 7 shows a view illustrating a state where a thin plate member is inserted into the clearance of the fabricated packing box. This figure shows an enlarged view of the front right portion of the packing box in a state where the outer lid part is closed, which is viewed from the top of the packing box.

FIG. 8 shows a view illustrating a state where a thin plate member is inserted into the clearance of the fabricated packing box. This figure shows a view of the part illustrated in FIG. 7, which is viewed from the bottom of the inside of the packing box.

DETAILED DESCRIPTION

Hereinafter, the embodiments of the present disclosure are described. FIG. 1 shows a schematic perspective view of the packing box according to one embodiment of this disclosure. FIG. 2 shows a development view illustrating a corrugated fiberboard member before fabrication of the packing box according to one embodiment of this disclosure. FIG. 3 shows a development view illustrating a state where the corrugated fiberboard member as illustrated in FIG. 2 does not have the projecting part, which is described below. From the viewpoint of easiness of understanding, the direction as illustrated in the arrow D₁ in FIGS. 2 and 3 is assumed a vertical direction which directs from the bottom to the top. Also, the direction as illustrated in the arrow D₂ in FIGS. 2 and 3 is assumed a direction toward the right from the left.

Referring to FIGS. 1 to 3, the packing box 11 according to one embodiment of this disclosure is a so-called generally rectangular parallelepiped shape. The packing box 11 is formed of a single sheet of a plate-like member that has force of restitution when it is folded. Specifically, the packing box 11 is formed by fabricating a corrugated fiberboard member 12a.

As recognized from the development view as illustrated in FIG. 2, the packing box 11 is formed by, for example, preparing a sheet of rectangular corrugated fiberboard member, then punches out the corrugated fiberboard member into a form as illustrated in FIG. 1, and finally sequentially folding the corrugated fiberboard member at the folding parts as illustrated in the dashed line. The packing box 11 houses an articles to be packed, such as a developer unit, a toner cartridge, or the like, which are consumables in the image forming device. FIG. 1 shows a toner cartridge 13 as an article to be packed, which is wrapped with a plastic bag.

The packing box 11 includes side wall parts 14a which are to be located, when the toner cartridge 13 is housed inward, in the lateral side, a bottom wall part 15a which is to be located in the lower side of the toner cartridge 13, a pair of inner flaps 16a and 17a which are to be mainly located in the upper side of the toner cartridge 13, and the outer lid parts 31 which is similarly to be mainly located in the upper side of the toner cartridge 13. The packing box 11 is formed of the side wall parts 14a and the bottom wall part 15a, and has a housing part 20 to house an article to be packed.

The corrugated fiberboard member 12a, which is to be folded to form the packing box 11, includes four sidewall forming parts 21a, 21b, 21c, and 21d, which constitute the side wall parts 14a, four bottom wall forming parts 22a, 22b, 22c, and 22d, which constitute the bottom wall part 15a, inner flaps 16a, 17a, and 19a, the outer lid parts 31, and partition part 43 which restricts the movement of the packed article in the packing box 11.

The packing box 11 formed of such a corrugated fiberboard member 12a includes side wall parts 14a and the bottom wall part 15a and the outer lid part 31. Also, the packing box 11 houses a toner cartridge 13 in the space surrounded by the side walls 14a and the bottom wall part 15a, and closes the above side of the toner cartridge 13 by the outer lid part 31 to pack the toner cartridge 13. The outer lid part 31 is provided consecutively with one side wall part 14a of side wall parts 14a and opens and closes the upper part of housing part 20 towards the opposed other side wall 14a. The inner flaps 16a, 17a, and 19a are provided consecutively with the other side wall parts and are to be folded inward.

The four bottom wall forming parts 22a, 22b, 22c, and 22d are provided consecutively from the lower end of the four sidewall forming parts 21a, 21b, 21c, and 21d, respectively. The outer lid part 31 is provided consecutively from the upper end of the sidewall forming part (one side wall part) 21a. The outer lid part 31 is located outermost at the top position after the packing box 11 is fabricated. The inner lid parts 41a and 42a are provided consecutively from the upper end of the sidewall forming part (other side wall part) 21c. After the packing box 11 is fabricated, the inner lid parts 41a and 42a are placed inside the outer lid part 31, namely, on the side of the space in which the cartridge 13 is to be housed.

A pair of inner flaps 16a and 17a are provided consecutively from the upper end of the sidewall forming parts 21b and 21d, respectively. The pair of the inner flaps 16a and 17a are also located inside the outer lid part 31 after packing box 11 is fabricated. The length of the inner flap 17a from the upper end of the sidewall forming part 21d is larger than the length of the flap 16a from the upper end of the sidewall forming part 21b. The inner flap 17a is configured to be folded at a plurality of points. After the toner cartridge 13 is housed in the packing box, the inner flap 17a is folded appropriately along the peripheral shape of the toner cartridge 13.

The four sidewall forming parts 21a to 21d are in a flat plate form, respectively, and are provided consecutively in the horizontal direction. Folding parts illustrated by dashed lines are located at each boundary of the four sidewall forming parts 21a to 21d. The sidewall forming parts 21a and 21c each have a rectangular shape which is longer in a horizontal direction. The sidewall forming parts 21b and 21d each have a rectangular shape which is slightly longer in a vertical direction. The vertical length of the four sidewall forming parts 21a to 21d are the same as one another. Each horizontal length of the sidewall forming parts 21b and 21d is approximately one-third of that of the sidewall forming parts 21a and 21c.

The sidewall forming parts 21a to 21d are to be folded at the folding parts located therebetween such that the periphery of the sidewall forming parts should form a rectangular shape when it is viewed from the vertical direction. Namely, the sidewall forming parts 21a to 21d is folded by approximately 90° to adjacent one of the sidewall forming parts 21a to 21d, respectively. Then, the sidewall forming parts 21a to 21d are formed into a square cylindrical shape by attaching a glue flap 23, which are provided consecutively on the left side of the sidewall forming part 21a, to the sidewall forming part 21d with an adhesive or the like. The side wall parts 14a are formed in this way.

The bottom wall part 15a is formed by interlocking the four bottom wall forming parts 22a, 22b, 22c, and 22d when sidewall forming parts 21a to 21d are folded into a rectangular shape. The bottom plate part 15a becomes the part which the toner cartridge 13 is to be put on. The four bottom wall forming parts 22a to 22d have projected and depressed portions which engage with each other. The four sidewall forming parts 21a to 21d are interlocked such that depression of the depressed portion and projection of the projected portion which are provided on the bottom wall forming parts 22a to 22d are engaged with one another when the four sidewall forming parts 21a to 21d are folded along the folding parts as illustrated in the dashed line.

A pair of the inner flaps 16a and 17a are folded inward after the sidewall forming parts 21a to 21d are folded into a rectangular shape, and before or after housing the toner cartridge 13. In this case, one inner flap 17a is interfolded to the edge of the toner cartridge 13, and the other inner flap 16a is folded after housing the toner cartridge 13.

The outer lid part 31 is to be folded along the folding part 24, which forms the boundary between the outer lid part 31 and the sidewall forming part 22a, to form the outer lid of the packing box 11. The outer lid part 31 is provided with a pair of perforations 32a and 32b, which extend horizontally. Notches 33a and 33b are provided around the horizontal ends of the perforations 32a and 32b. These notches 33a and 33b makes it easy to take out the packing box 11 from a certain place by sticking fingers in the notches 33a and 33b. By pulling and breaking a part 34 of the outer lid part 31 along the perforations 32a and 32b, the outer lid part 31 can be opened without releasing the locking device which is described below. Further, perforations 35a, 35b, 36a, and 36b are provided near the each horizontal end of the perforation 32b. By breaking a part of the outer lid part 31 along the perforations 35a, 35b, 36a, and 36b, a through hole which penetrates the outer lid part 31 in the thickness direction can be provided at a part of the outer lid part 31.

The upper edge of the outer lid part 31 is provided with a tuck 37, which extends upward, namely in the direction as illustrated by the arrow D₁. This tuck 37 is provided such that it extends consecutively from the outer lid 31, more specifically, such that it extends upward continuously from

the position provided with the upward perforation 32a. The tuck 37 has a horizontally long rectangular shape. The tuck 37 can be folded along the perforation 32a. Namely, the tuck 37 extends from the edge of the top of the outer lid part 31, and is configured to be foldable. The tuck 37 is used when the outer lid part 31 is closed to the side of the side wall part 14a.

On the outer lid part 31, a pair of extending parts 38a and 38b are provided. The extending parts 38a and 38b extend in a horizontal direction of the tuck 37, namely, one extends in the direction shown by the arrow D₂ and the other extends in the reverse direction thereof. A pair of the extending parts 38a and 38b are each provided to extend in a horizontal direction. Namely, a pair of the extending parts 38a and 38b each cross the tip edge of the tuck 37 and extend from the side edge. The pair of extending parts 38a and 38b can be folded along the folding parts 39a and 39b, respectively. Namely, the pair of extending parts 38a and 38b are each configured to be foldable to the tuck 37. The vertical length of each of the pair of the extending parts 38a and 38b is configured such that it is slightly shorter than the vertical length of the tuck 37.

Similarly to the above pair of the inner flaps 16a and 17a, the inner flap 19a is to be folded after the sidewall forming parts 21a to 21d are folded into a rectangular shape, and before or after housing the toner cartridge 13. The inner flap 19a is to be folded at the folding part 25a, to form the inner lids 41a and 41b. Namely, on the side of the side wall parts 14a of the inner flap 19a, the inner lids 41a and 41b, which are consecutively provided and are to be placed inside the outer lid part 31, is provided. Furthermore, the inner flap 19a is to be folded at the folding part 25b, to form a partition part 43, which spreads vertically to divide the inner space in the packing box 11. The partition part 43 restricts the movement of the toner cartridge 13 that is housed in the packing box 11.

The inner flap 19a is provided with a slit 44a through which the tuck 37 and a pair of the extending parts 38a and 38b can be inserted. The horizontal width L₁ of the slit 44a is slightly wider than the horizontal width L₂ of the tuck 37. Here, the slit 44a has a shape that is cut along the shape of another side wall part 14a. The inner lid parts 41a and 42a are divided horizontally by the slit 44a. The inner lid parts 41a and 42a are provided with jutting parts 45a and 45b which juts out to the side of the slit 44a. The jutting parts 45a and 45b forms an interfere part that interferes with a pair of the extending parts 38a and 38b that returns to the original shape to some extent after they are inserted into the slit 44a. Namely, the packing box 11 comprises an interference part that is to be folded from the side edge, which crosses the side wall part 14a of the inner flap 19a.

Another rectangular jutting parts 47 projecting into the side of the slit 44a is provided also on the side of the partition part 43 side. This jutting part 47 is to be folded and is also used to restrict the movement of housed toner cartridge.

Here, the inner lid part 41a is provided with a projecting part 48a which projects outward from the left side end in the FIG. 2, namely, which projects leftward in the reverse direction as illustrated by the arrow D₂. The inner lid part 42a is provided with a projecting part 48b which projects outward from the right side end in the FIG. 2, namely, which projects rightward in the direction as illustrated by the arrow D₂. Namely, the inner lids 41a and 42a are provided with a pair of projecting parts 48a and 48b each of which projects outward from the ends of the outer sides.

A pair of the projecting parts 48a and 48b each have a generally rectangular shape. The projecting length of the

projecting part 48a, which is illustrated as the length L_4 in FIG. 2, is configured to be longer than the extending length of the extending part 38a, which is illustrated as the length L_3 in FIG. 2. The same shall apply to the relation with the length of the projecting part 48b and the length of the extending part 38b. A pair of projecting parts 48a and 48b are folded inward along the folding parts 49a and 49b, respectively. Namely, the projecting parts 48a and 48b are configured to be folded relative to the inner lid parts 41a and 42a, respectively.

Once a pair of projecting parts 48a and 48b are folded from the side edge that crosses another wall forming part 14a of the inner flaps 19a, they are located on the course from the outside of the packing box 11 to the pair of the extending parts 38a and 38b which are inserted into the slit 44a. A pair of the projecting parts 48a and 48b forms an obstructive part to obstruct the contact of other members with a pair of the extending parts 38a and 38b which are inserted into the slit 44a. Namely, the obstructive part includes a pair of the projecting parts 48a and 48b that extend from the side edge of the inner lids 41a and 41b to the course as mentioned above.

The development view of the packing box which does not have a pair of the projecting parts 48a and 48b is shown in FIG. 3. Namely, the corrugated fiberboard member 12b includes the side wall parts 14b which are to be located in the lateral side when the toner cartridge 13 is housed inward, the bottom wall part 15b which is to be located in the lower side of the toner cartridge 13, a pair of the inner flaps 16b and 17b which are to be mainly located in the upper side of the toner cartridge 13, and the outer lid part 30 which is similarly to be mainly located in the upper side of the toner cartridge 13. This constitution does not include any pair of projecting parts that projects outward from each of the outer ends of the inner wall parts 41b and 42b which are divided by the slit 44b.

Then, the way to fabricate the packing box 11 from the corrugated fiberboard member 12a is described. FIG. 4 shows a flow chart illustrating a representative process of fabricating the packing box 11 in which the toner cartridge 13 is housed.

Referring to FIG. 4, at first, the corrugated fiberboard member 12a having the shape as illustrated in FIG. 2 is prepared. Then, the sidewall forming parts 21a to 21d are folded along the folding parts (corresponding to the step S11 in FIG. 4. Hereinafter, the word "step" is omitted). In this case, the sidewall forming parts 21a to 21d are folded such that the angle between adjacent two sidewall forming parts 21a to 21d should be approximately 90°.

However, the corrugated fiberboard member 12a is provided in a state where it is folded beforehand and the glue flap 23 and the sidewall forming part 21d are attached thereto. In this case, the front surface of the glue flap 23 and the backside surface of the sidewall forming part 21d, namely, a surface which is located inward, may be joined with an adhesive. Alternatively, a stapler for corrugated fiberboards may be used to join them.

Then, the depressed portion and the projected portion of the bottom wall forming parts 22a to 22d are fitted together, to form the bottom wall part 15a (S12). In this case, the bottom wall part 15a is formed by deforming the bottom wall forming parts 22a to 22d and the sidewall forming parts 21a to 21d to some extent and fitting the depressed portion and the projected portion with one another to interlock them together.

Then, one inner flap 19a is folded along the folding parts 25a, to form the inner lids 41a and 42a (S13). Here, the

outside flap 19a, which is provided consecutively with the sidewall forming part 21c, is folded inward to form the inner lid parts 41a and 42a.

Then, one inner flap 19a is further folded along the folding parts 49a and 49b to form a pair of the projecting parts 48a and 48b (S14). Namely, a pair of the projecting parts 48a and 48b are formed by folding them along the side edges of the inner lid parts 41a and 41b. A pair of the projecting parts 48a and 48b which are formed in a folded state extend from the inner lid parts 41a and 42a to the lower side.

Then, an inner flap 19a is further folded along the folding parts 25b to form the partition part 43 (S15). Here, the toner cartridge 13 is housed inside. In this case, the outside flap 19a may be folded while the toner cartridge 13 is housed inside. At the same time, one inner flap 17a is folded. The steps S14 and S15 may be performed simultaneously, or be performed in any order.

After the toner cartridge 13 is housed, the other inner flap 16a is folded inward (S16). At this point in the process, the packing box 11 is in a state where all the folding parts except the outer lid part 31 are folded, as illustrated in FIG. 1.

Then, the outer lid part 31 is folded along the folding part 24 while a pair of extending parts 38a and 38b are folded along the folding parts 39a and 39b (S17). In this case, the extending part 38a is folded back inward with fingers 26 as illustrated in FIG. 5. FIG. 5 shows a view illustrating a folded state of the extending part 38a which is folded back inward.

Then, the tuck 37 and a pair of the extending parts 38a and 38b are inserted in the slit 44a while the state where a pair of the extending parts 38a and 38b are folded is maintained (S18). Namely, the tuck 37 is inserted into the slit 44a in the state where a pair of the extending parts 38a and 38b are folded. In this case, as illustrated in FIG. 6, the state where a pair of the extending parts 38a and 38b are folded is maintained by holding them with fingers 26, and the outer lid part 31 is folded in the direction as illustrated by the arrow D₃ in FIG. 6. Then, the tuck 37 and a pair of the extending parts 38a and 38b are inserted into the slit 44a. FIG. 6 shows a view indicating a state where the tuck 37 and a pair of extending parts 38a and 38b are being inserted into the slit 44a while the state where the tuck 37 and a pair of the extending parts 38a and 38b are folded is maintained. In FIG. 6, fingers holding the extending part 38b is not illustrated.

Thus, the packing box 11 according to one embodiment of this disclosure is fabricated. After the tuck 37 and a pair of the extending parts 38a and 38b are folded and then inserted into the slit 44a, a pair of the folded extending parts 38a and 38b restore to the original shape to some extent. Thus, by hooking up a pair of the extending parts 38a and 38b which restored to the original shape to some extent with the jutting parts 45a and 45b as the wall parts which constitute the slit 44a, the packing box 11 is locked such that the state where the outer lid part 31 is closed relative to the side of the side wall part 14a should be maintained. Namely, after the insertion, a pair of the extending parts 38a and 38b restrict the release of the outer lid part 31 by restoration in the direction crossing the extending direction of the slit 44a. A pair of the folded projecting parts 48a and 48b which are provided on the side of the side wall parts 14a are provided on the course from the outside of the packing box 11 to a pair of the extending parts 38a and 38b which are inserted into the slit 44a, and obstruct the contact of the other members with a pair of the extending parts 38a and 38b which are inserted into the slit 44a. Namely, the obstructive part

includes a pair of the projecting parts **48a** and **48b** which extend from the inner lids **41a** and **42b** to the course as described. The obstructive part is placed between the course that reaches from the clearance between the top edge of a pair of the side wall parts **14a** that cross the other side wall part **14a** and the inner flap **19a** to a pair of the extending parts **38a** and **39b**, and obstructs the approach from the outside of packing box **11** to a pair of the extension parts **38a** and **38b**.

More information about this obstructive part is now described. FIGS. 7 and 8 show views illustrating a state where a thin plate member is inserted into the clearance of the fabricated packing box **11**. FIG. 7 shows an enlarged view of the upper portion, in this case, the front right portion of the packing box **11** in a state where the outer lid part is closed, which is viewed from the top of the packing box **11**. FIG. 7 is a figure which is viewed from the direction which is reverse to the direction as illustrated in the arrow D_1 in FIG. 2. FIG. 8 shows a view of the part illustrated in FIG. 7, which is viewed from the bottom of the inside of the packing box **11**. FIG. 8 is viewed from the direction as illustrated in the arrow D_1 in FIG. 2.

Referring to FIGS. 7 and 8, in order to release the lock mechanism by drawing the extending part **38b** from the slit **44a**, the thin plate member **27** is inserted into the clearance **28** between the sidewall forming part **21d**, which forms the side wall part **14a**, and the outer lid part **31**, and contacting it with the extending part **38b**, to make the extending part **38b** in a folded state, namely, a state at which the thin plate member **27** is being inserted. However, a projecting part **48b** projects on the course from the clearance **28** to the extending part **38b**. Thus, the thin plate member **27** cannot contact with the extending part **38b**, and thus, the extending part **38b** cannot be in a folded state. Therefore, it becomes difficult to release the lock of such packing box **11**.

In this case, because the projecting lengths of a pair of the projecting parts **48a** and **48b** are longer than the extending lengths of a pair of the extending parts **38a** and **38b**, respectively, the contact of the other members with a pair of the extending parts **38a** and **38b** are more surely obstructed.

In the above detailed description of the preferred embodiment, the projecting parts **48a** and **48b** are formed by folding a part of the inner lid parts **41a** and **42b**. However, the embodiment of the invention is not limited to this constitution. For example, it is possible to form the projecting parts **48a** and **48b** on the course from the outside of the packing box **11** to a pair of the extending parts **38a** and **38b**, which are inserted into the slit **44a**, such that they extend from the backside surface, namely, the inner side surface of the side wall forming part **21c**.

In the above detailed description of the preferred embodiment, a pair of the projecting parts in response to each pair of the extending parts. However, the embodiment of the invention is not limited to this constitution. Alternatively, if only one extending part is provided, it is sufficient to provide only one corresponding projecting part. It is sufficient that the packing box has at least one projecting part.

In the above detailed description of the preferred embodiment, the projecting lengths of a pair of the projecting parts **48a** and **48b** are longer than the extending lengths of a pair of the extending parts **38a** and **38b**, respectively. However, the embodiment of the invention is not limited to this constitution. Alternatively, each length may be equal, or the projecting length of a pair of the projecting parts **48a** and **48b** may be shorter than the extending length of a pair of the extending parts **38a** and **38b**, respectively. In this case, when the projecting parts are provided on the side which is nearer

to the clearance, it possible to obstruct the contact of the other member with the extending parts.

In the above detailed description of the preferred embodiment, a cushioning material may be provided in a certain area of the inside of the packing box.

In the above detailed description of the preferred embodiment, a corrugated fiberboard member is punched out in a shape as illustrated in FIG. 2 and folded at the folding part to form a packing box. However, the packing box is not limited to this embodiment, and may be formed by laminating a plurality of members, for example.

The embodiments described above are to be considered in all aspects as illustrative only and not restrictive in any manner. The scope of the invention is, therefore, indicated by the appended claims rather than by the foregoing description. All changes which come within the meaning and range of equivalency of the claims are to be embraced within their scope.

The packing box according to this disclosure is used particularly effectively when a locking structure which cannot be easily released is required.

What is claimed is:

1. A packing box, comprising:
a plurality of side wall parts that compose peripheral walls,
a bottom wall part,
a housing part to house an article, the housing part being composed of the plurality of side wall parts and the bottom wall part,
an outer lid part to open and close an upper part of the housing part, the outer lid part being provided consecutively with a first side wall part of the plurality of side wall parts,
a tuck that extends from an edge part opposed to a consecutive part between the first side wall part and the outer lid part, and is configured to be folded,
at least one extending part that extends from a side edge of the tuck in a direction crossing a folding part between the tuck and the outer lid part,
an inner flap that is provided consecutively with a second side wall part, the second side wall part being other than the first side wall part, and being opposed to the first side wall part, and is configured to be folded inward,
a slit that is provided in the inner flap and is cut along the second side wall part,
an obstructive part that is configured to be folded along a folding part from a side edge of the inner flap crossing the second side wall part,
wherein the tuck is configured to be inserted into the slit so as to be contacted with the slit along the second side wall part while the extending part is folded,
the extending part restricts, once the tuck is inserted, release of the outer lid part by restoration to the original state in a direction crossing an extending direction of the slit,
an inner lid part that is provided consecutively with the second side wall part and is to be placed inside the outer lid part is provided on a side of the second side wall part of the inner flap, and
the obstructive part is configured to be placed in a course from a clearance between the top edge of the first side wall part which crosses the second side wall part, and the inner flap to the extending part, and the obstructive part includes a projecting part configured to be folded along a side edge of the inner lid part such that the projecting part is opposed to the first side wall part

11

crossing the second side wall part, and obstructs approach from the outside of the packing box to the extending part.

2. The packing box according to claim 1, wherein the tuck is provided with a pair of extensions each 5 composed of the extending part at both ends, and a pair of projections each composed of the projecting part are provided in response to each pair of the extending parts.
3. The packing box according to claim 1, wherein 10 a projecting length of the projecting part is configured to be longer than an extending length of the extending part.
4. The packing box according to claim 1, wherein the packing box is formed of a sheet of a plate-like 15 member that has force of restitution in a folded state.
5. The packing box according to claim 1, further comprises a partition part that is configured to be consecutively 20 foldable with an edge of the inner flap opposed to a consecutive part between the inner lid part and the second side wall part so that the partition part is arranged corresponding to the second side wall part, and the projecting part is formed in a substantially rectangular 25 shape, and is arranged so as to be sandwiched between the second side wall part and the partition part.
